UNITED STATES PATENT OFFICE.

JOSEF AUER, OF NEW YORK, N. Y., ASSIGNOR OF ONE-FOURTH TO EDMUND WALTUCK,
OF NEW YORK, N. Y.

HYDROMOBILE.

1,232,751.

Specification of Letters Patent. Patented July 10, 1917.

Application filed May 1, 1917. Serial No. 165,698.

To all whom it may concern:

Be it known that I, JOSEF AUER, a citizen of the United States, and a resident of New York city, in the county and State of New 5 York, have invented certain new and useful Improvements in Hydromobiles, of which the following is a specification.

This invention relates to a hydromobile of novel construction, which is well adapted 10 for sporting purposes and may be folded up into a small compass when placed out of commission.

The invention consists in the various features of novelty more fully pointed out in 15 the specification and appended claims.

In the accompanying drawing:

Figure 1 is a plan partly in section, of a hydromobile embodying my invention;

Fig. 2, a longitudinal section on line 2—2 20 Fig. 1;

Fig. 3, a section through one of the floats, showing it collapsed;

Fig. 4, a cross section on line 4—4 Fig. 1;

Fig. 5, a longitudinal section on line 5—5 25 Fig. 2, and

Fig. 6, a detail of the rack and pinion transmission.

The hydromobile is constructed on the catamaran principle, being composed of two 30 floats that carry a cross deck or platform. Each float is formed in three cylindrical sections, of which the central section 1, is adapted to telescope the stern section 2, which in turn is adapted to telescope the 35 bow section 3. The central section 1, is split longitudinally along its inner side so that it may yield somewhat during the telescoping operation, and is here provided with a pair of spaced laterally extending flanges 40 4 the upper one of which supports the platform 5. This platform is slotted along its edges and is here engaged by bolts 6 that pass likewise through apertures of flanges 4, and through a packing strip 7 interposed 45 between said flanges. By removing nuts 8 carried by the bolts, the platform may be disconnected from the float-sections, so that in this way, the device may be readily dismembered.

50 The rear float sections 2 are open at the front and back, and may be closed watertight at the back by hinged lids 9, while a packing ring 10 is interposed between the overlapping ends of sections 1 and 2. The 55 front float section 3, has a pointed or coni-

form bow, while a similar packing ring 11 is interposed between the overlapping sections 1 and 3, the thickness of ring 11 being however, somewhat greater than that of ring 10 in order to compensate for the difference 60 in diameters between the sections 3 and 2.

From platform 5, depends a housing 12, containing the bearings for the shaft 13 of the propeller screw 14. The latter is operated in the following manner: A hand lever 65 15 is adapted to be inserted into the socketed end of a two arm lever 16 turning on fulcrum 17. To opposite ends of lever 16 are pivoted by links 18, a pair of racks 19, engaging pinions 20 loose on an upright shaft 70 21. In proximity to each pinion there is fast on shaft 21, a ratchet wheel 22 engaged by a pawl 23 pivoted to the pinion, the teeth of the two ratchet wheels being opposed to each other, 75

Shaft 21 is by bevel wheels 24 intergeared with propeller shaft 13, so that by moving hand lever 15 alternately forward and backward, the ratchet wheels will impart continuous rotary movement to shaft 21 and 80 consequently to propeller 14, the pawl of the inert wheel 22 gliding freely over the teeth thereof, as will be readily understood.

In order to hold racks 19 to their pinions 20, they are furnished with flanged backs 85 engaging grooved guide blocks 25, which by means of set screws 26, are mounted on a fixed post 27, of housing 12.

Platform 5 is further provided with a rudder 28 and with a saddle 29, mounted on 90 a collapsible support, which consists of an upright 30, a diagonal brace 31, and a horizontal rod 32, the latter being received within a suitable guide 33 of the platform to which it may be held by a clamp screw 34. 95 Thus the saddle may be removed from the platform and then its support may be folded so as to occupy a minimum amount of space.

The correlation of the parts is such that 100 when the platform is disconnected from the floats and the sections of the latter are telescoped, the platform together with all its appurtenances may be readily slipped into one of the floats through lid 9, the drawing 105 showing the width of the platform somewhat exaggerated for the sake of displaying the propelling mechanism on a larger scale.

It will be seen that the hydromobile constructed as described is well adapted for use 110

especially on beaches, rivers, or lakes, that it may be readily operated, and that it can be folded up to occupy a minimum amount of space during portage or storage.

5 I claim:

1. A hydromobile comprising a pair of floats, each composed of a longitudinally split and flanged section, a stern section and a bow section adapted to be telescoped by 10 the flanged section, and a platform adapted to removably engage the flanged section.
2. A hydromobile comprising a pair of floats, each composed of a central longitudinally split section, a stern section and a bow 15 section adapted to be telescoped by the central section, a packing interposed between the central section and the stern section; a further packing interposed between the central section and the bow section, and a platform 20 form adapted to be removably connected to the central section.
3. In a hydromobile, a two arm lever, a pair of racks pivoted thereto, a pair of pinions engaged by the racks, a pair of oppositely disposed ratchet wheels, pawls on the 25

pinions that engage said ratchet wheels, a shaft on which the ratchet wheels are mounted, and a propeller shaft intergeared with the first named shaft.

4. A hydromobile comprising a pair of 30 telescopic floats, a platform removably secured thereto, a saddle, a foldable support for said saddle, and means for removably securing said support to said platform.

5. A hydromobile comprising a pair of 25 telescopic floats, a platform removably secured thereto, a foldable saddle and hydromobile propelling means carried by the platform, said platform, saddle and propelling means being adapted to be received within 40 one of the floats.

6. A hydromobile comprising a pair of 45 tubular floats, each composed of a plurality of telescoping sections, packings between said sections, a water tight lid on the rear-most section, and a removable platform carried by the floats and adapted to be projected into either one of said floats.

JOSEF AUER.
